OF OHIO.

METAL FENCE-POST AND WIRE-FASTENING MEANS THEREFOR.

1,136,471.

Specification of Letters Patent.

Patented Apr. 20, 1915.

Application filed March 27, 1914. Serial No. 827,528.

To all whom it may concern:

Be it known that we, HENRY L. LEILICH and FREDERICK W. BURGER, citizens of the United States, and residents of Delphos, in the county of Allen and State of Ohio, have invented a certain new and useful Metal Fence-Post and Wire-Fastening Means Therefor; and we do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to metal fence posts and to wire securing means therefor, but is not restricted to such use as it may be used in any connection for which it may be adapted or appropriate.

The object of the invention is the provision in conjunction with a simple, inexpensive and durable fence post, which is formed of sheet-metal rolled or shaped in desired form in cross-section, of means for securing the spaced edges of the post together in rigid relation and for securing the fence wires to the post, such means being adjustable to suit the relative spacing of the fence wires.

A further object of the invention is the provision of simple and efficient fastening means for fence wires, which is easy of application and capable of adjustment relative to a post to clamp a wire thereto at one side or the other of the longitudinal center of the post, as it may be desired to miss a vertical stay wire of the fence.

Further objects and advantages will be apparent from the following detailed description.

The invention is fully described in the following specification, and while, in its broader aspect it is capable of embodiment in numerous forms, a preferred embodiment thereof is illustrated in the accompanying drawings, in which,—

Figure 1 is an elevation of a post embodying the invention with a fence attached thereto. Fig. 2 is an enlarged cross-section on the line x , x in Fig. 1. Fig. 3 is an enlarged side elevation of a portion of the post and one of the wire fastening means attached thereto, and Fig. 4 is a longitudinal section on the line y , y in Fig. 2, with the bolt in full.

Referring to the drawings, 1 designates a fence post which is made of sheet-metal, such for instance, as galvanized iron of suitable gage, which metal is so formed or shaped as to make the post hollow and preferably circular in cross-section, with the side edges of the metal spaced apart a suitable distance to provide a longitudinal slot 2 in one side of the post. The post is preferably longitudinally tapered, as is customary in articles of this class. The wire fastening means preferably employed in connection with this post comprises a clip 3 and a retaining bolt 4 therefor, which bolt has its shaft projected through the post slot 2 for free sliding movements lengthwise thereof.

The clip 3 preferably comprises a casting, which has its inner side concaved in cross-section to adapt it to seat against the post side to which it is firmly clamped by the bolt 4, which passes through a central hole 5 therein. The clip 3 is provided at one side of its vertical center, preferably at each the upper and lower edges thereof, with a vertically projecting tongue 6, which is provided on its inner side with a cross-groove 7 for fitting over a line-wire 8 of a fence. The positioning of the tongue 6 in offset relation to the vertical center of the clip and to the post slot performs a two-fold function, namely, of enabling a wire to be clamped to the post at a side of its slot, and of enabling the tongues to be disposed at either side of the post slot upon a half turning of the clip around the bolt 4 for such purpose, to effect a gripping of a wire at one side or the other of the slot, as it may be desired to escape a vertical stay-wire 9 of the fence, thus rendering the clip flexible in its application. It may happen that a stay wire of a fence will be directly in line with the securing tongues 6, which would cause some injury to the fence to permit a fastening thereof if it were not possible to shift the clip so that the tongues would stand on the opposite side of the bolt to the stay wire. It will be understood that while two tongues 6 are shown, one only may be provided if desired, or the tongues may be placed at different corners from those shown. The tongues 6 are of such form

that while a wire held thereby cannot become disengaged from the post, it is free to move horizontally under varying temperature conditions or from mechanical causes.

5 The inner side of the clip is preferably provided with a recess or countersink 10 provided therein in complementary relation to the bolt head 4^a to permit the registering edge portions of the metal forming the post 10 to be drawn into the recess by the bolt head upon a tightening of the bolt, as shown at 11 in Fig. 4. The interengaging of the post metal with the clip in this manner not only holds the clip in fixed relation to the post 15 and prevents a sagging of the line-wires, but also serves to lock the edge portions of the post metal against outward movements, thereby being quite an important feature in connection with a post of the character described. Should the bolt head and recess 10 be of rectangular form, the bolt shank and hole 5 in the clip are preferably made square to prevent a relative turning of the clip and bolt to insure a true registering of the bolt 20 head and recess. When the clips are all fastened the shaft of the post is practically one continuous piece.

It is evident that the clips may be adjusted longitudinally of a post to suit the 30 positions of the line wires of a fence, and that the wire engaging tongues may be fixed at one side or the other of the post slot as it may be desired to escape a stay wire of the fence.

35 We wish it understood that our invention is not limited to any specific construction, form or arrangement of the parts except in so far as such limitations are specified in the claims.

40 Having thus described our invention, what we claim as new, and desire to secure by Letters Patent, is,—

1. The combination with a fence post having bearing surfaces which are spaced transversely thereof, of a wire holding clip secured to one side of said post and provided with wire engaging tongues projecting therefrom in opposite directions longitudinally of the post and transversely offset from the 45 space intermediate the post bearing surfaces, said clip being adjustable to place said tongues into gripping coaction with either of said bearing surfaces.

2. The combination with a fence post having a bolt receiving opening in a side thereof and a bearing surface at each side of said opening, of a wire holding clip extending 55 across said opening transversely of the post

and having a bolt receiving opening in register with the post opening, said clip also 60 having wire engaging tongues projecting therefrom in opposite directions longitudinally of the post and offset from the clip opening transversely of the post, the clip being shiftable to place said tongues in 65 clamping coaction with one or the other of said bearing surfaces, and means projecting through said clip and post openings for securing the clip in position relative to the 70 post.

3. In combination, a fence-post formed of sheet-metal with the longitudinal edges of said metal spaced to form a slot lengthwise of the post, a wire securing clip for seating against a side of the post cross-wise of the 75 slot and having a recess in its inner side, and means projecting through the clip and post slot for securing the clip in adjusted position to the post and for drawing edge portions of the post at the sides of the slot 80 into said recess.

4. In combination, a fence-post formed of sheet-metal with the edges of said metal spaced to provide a slot lengthwise of the post, a wire 85 engaging clip for seating against the post crosswise of the slot and having a hole therein and a recess at its inner side, and a bolt projected through said hole and the post slot and adapted when tightened to clamp the clip in adjusted relation to the post and to draw registering edge portions of the post metal into said recess.

5. In combination, a fence-post of sheet-metal with the edges of said metal spaced to provide a slot lengthwise of the post, a wire 95 engaging clip for seating against the post crosswise of the slot and having a hole therein and a recess at its inner side, and a bolt projected through said hole and the post slot and adapted when tightened to 100 clamp the clip in adjusted relation to the post and to draw registering edge portions of the post metal into said recess, said clip having vertically projecting wire engaging 105 tongues which are offset from the bolt hole therein to facilitate a placing of the tongues at one side or the other of the slot upon a half turning of the clip relative to the post.

In testimony whereof, we have hereunto signed our names to this specification in the 110 presence of two subscribing witnesses:

HENRY L. LEILICH.
FREDERICK W. BURGER.
